SAW-TOOTH VOLTAGE GENERATOR

Harold W. Beach, Fort Wayne, Ind., assignor, by
mesne assignments, to Farnsworth Research
Corporation, a corporation of Indiana

Application October 28, 1946, Serial No. 706,255

4 Claims. (Cl. 250—27)

1

This invention relates to saw-tooth wave generators and particularly to generators capable of producing a push-pull voltage of saw-tooth wave form having good linearity and relatively high voltage.

In order to deflect the electron beam of a cathode ray tube it is necessary to impress upon the deflecting system a sweep voltage varying periodically between maximum and minimum amplitude limits in a predetermined manner. In oscilloscopes, television tubes and the like, the wave form of such a sweep voltage generally has the shape of a saw-tooth. Ordinarily the voltage variation of the sweep wave is required to be as linear as possible.

Many devices for generating an electron beam deflecting voltage have heretofore been devised. In general, those of such devices which are capable of generating saw-tooth waves having good linearity are incapable of producing these waves at any appreciable voltage. Such devices are generally satisfactory for employment with cathode ray tubes having conventional deflecting systems, such as two pairs of deflecting electrodes mounted within the tube at right angles to one another and in two different planes along the path of the beam. Devices of this character, however, are not suitable for use with a cathode ray tube wherein the deflecting system comprises a plurality of elongated electrodes located around the path of the beam substantially in the same plane. According to present practice the deflecting voltages are impressed upon such electrodes by means of a voltage distributing network having the general form of a balanced bridge arrangement of a plurality of impedance devices such as resistors. Networks of this character generally require an appreciable power input. Saw-tooth wave generators of the prior art may not be successfully employed in conjunction with networks of the character described by reason of their inability to produce a saw-tooth voltage which has both the required linearity and the relatively high voltage.

Accordingly, it is one of the objects of the present invention to provide a novel generator capable of producing a substantially linear saw-tooth wave of appreciable voltage magnitude.

Another object of the invention is to provide a saw-tooth wave generator capable of producing a balanced push-pull voltage wave of good linearity and of appreciable magnitude.

Also, according to conventional practice a saw-tooth wave generator is coupled to the deflecting system which it is to energize through the agency of condensers. In television practice the saw-tooth wave generator which functions to supply the horizontal deflecting energy produces a wave having a frequency of the order of 15,000 cycles per second. At such a frequency the condensers

2

used to couple the generator to the deflecting system may be quite small in value and yet have small reactances. Condensers having small reactances do not perceptibly affect the wave form of the saw-tooth deflecting energy and, therefore, there is produced comparatively no distortion from linearity of the wave. However, the saw-tooth wave generator which furnishes energy to the deflecting system for effecting vertical movement of the beam produces a saw-tooth voltage having a frequency of approximately 60 cycles per second. At this relatively low frequency the condensers which must be used to couple the generator to the deflecting system are of comparatively high values in order to have small reactances. Not only are such components bulky, thereby utilizing considerable space in the equipment, but also by reason of their relatively high values effect an appreciable distortion from linearity of the saw-tooth wave. Consequently any advantages which may be obtained by employing a generator of a saw-tooth wave having good linearity may be nullified to a considerable extent by the coupling condensers.

Therefore, it is still another object of the invention to provide, in conjunction with a saw-tooth wave generator capable of producing a wave having good linearity and appreciable voltage, a novel coupling arrangement between the generator and the electron beam deflecting system.

In accordance with the present invention there is provided a vacuum tube having at least an anode, a cathode and a control grid which is connected in the circuit with other components for developing a substantially linear saw-tooth voltage wave of considerable amplitude. The anode and the cathode of this tube are connected respectively through individual circuits including impedance devices to a source of space current. Conduction of space current through the tube and the impedance devices connected in the output circuit, thereof is varied in time according to a saw-tooth function under the control of a similarly varying voltage impressed upon the control grid. The voltage for impression upon the control grid is derived from a circuit having a capacitive reactance of a magnitude depending upon the frequency at which it is desired to generate the saw-tooth wave. This circuit is supplied with charging current through an impedance device connected in series therewith. This impedance device is coupled to the control grid and cathode of the vacuum tube in such a manner that at all times during the cycle a substantially constant potential difference is maintained across the impedance device. Periodically the capacitive reactance circuit is discharged through a circuit which may be rendered conducting under the control of a series of relatively

short time-spaced impulses. The anode and cathode of the tube are coupled to a load circuit such as a deflecting system, the mid point of which may be connected to a datum potential such as ground.

In accordance with an additional feature of the instant invention, the vacuum tube may be coupled to the load circuit by means of one or more glow discharge devices such as neon tubes. In one such arrangement these discharge devices may be connected in series between the anode of the tube and one terminal of the load circuit in which case the cathode is coupled to the other terminal of the deflecting system and the impedance between this latter terminal and the mid point of the load circuit serves as the cathode follower impedance for the tube.

For a better understanding of the invention together with other and further objects, thereof, reference is made to the following description taken in connection with the accompanying drawing and its scope will be pointed out in the appended claims.

In the accompanying drawing:

Fig. 1 is a circuit diagram of apparatus embodying one form of the invention, particularly adapted for operation at a relatively high frequency; and

Fig. 2 is a circuit diagram of apparatus embodying another form of the invention which includes a novel coupling arrangement and which is particularly well suited for operation at a relatively low frequency.

Reference will be made first to Fig. 1 wherein the apparatus disclosed is arranged particularly for operation at a relatively high frequency of the order of 15,000 cycles per second, for example. The saw-tooth wave generator includes a vacuum tube 11 which preferably is a pentode. The anode of this tube is connected through an impedance device such as a resistor 12 to the positive terminal of a source of space current, diagrammatically illustrated as a battery 13. The negative terminal of this battery is connected to ground. The cathode of the tube is connected through an impedance device such as a resistor 14 to ground. In order to generate a balanced push-pull saw-tooth voltage the resistors 12 and 14 should be of approximately the same values. The suppressor grid 15 of the tube 11 is directly connected to the cathode. The screen grid 16 of this tube is connected to the anode. The control grid 17 is connected to a capacitive reactance circuit which includes a capacitance 18. At the relatively high frequency specified, a part, at least, of this capacitance may be the inherent capacitance between the control grid 17 and ground.

There is provided for the capacitive reactance circuit including the capacitance 18, a circuit for supplying charging current thereto. This circuit comprises a resistor 19 connected between the positive terminal of the battery 13 and the anode of a diode 21, the cathode of which is connected in series with a resistor 22 and the capacitance 18. A condenser 23 is provided to couple the cathode of the tube 11 to the terminal of the resistor 22 which is connected to the cathode of the diode 21.

The capacitive reactance circuit also is provided with a discharging circuit. This circuit includes a vacuum tube 24 which preferably is a pentode. The anode of this tube is directly connected to the ungrounded terminal of the capacitance 18. The capacity to ground of the

anode serves as the major portion of the capacitance 18. The cathode of the tube 24 is connected to ground through a resistor 25 which is by-passed by a condenser 26. The suppressor grid 27 of the tube 24 is connected to the cathode. The screen grid 28 of this tube is connected through a resistor 29 to the positive terminal of the battery 13 and is by-passed to ground by a condenser 31. The control grid 32 of the tube 24 is coupled by a condenser 33 to one terminal of a source 34 of synchronizing impulses which are of positive polarity relative to ground. The other terminal of the impulse source is grounded.

The anode of the tube 11 is coupled by a condenser 35 to one terminal of a load circuit shown diagrammatically by resistors 36 and 37 of substantially equal values. The cathode of the tube 11 is coupled by a condenser 38 to the other terminal of the load circuit. The junction point between the load circuit resistors is connected to ground. This arrangement provides a load circuit which for alternating currents has a balanced impedance relative to ground. For example, in a successfully operated embodiment of the invention, the resistors 12 and 14 had values of 10,000 ohms and the resistors 36 and 37 had values of 15,000 ohms. Thus, from both the anode and the cathode of the tube 11, the effective alternating current load circuit impedance to ground was 6,000 ohms, each 10,000 ohm resistor being effectively coupled in parallel with one of the 15,000 ohm resistors.

Referring now to the operation of the embodiment of the invention shown in Fig. 1, assume that the conditions which obtain in the various circuits of the apparatus are those corresponding to the start of a cycle of the saw-tooth voltage wave to be developed. Under these conditions the tube 24 is in a non-conducting state and the tube 11 is in a state of minimum space current conduction. The capacitance 18 is in a state of minimum charge. The voltage of the anode of the tube 11 is at its maximum positive amplitude and the voltage at the cathode of this tube is at its minimum positive amplitude. The control grid 17 is at its maximum negative potential relative to the cathode of the tube 11.

Charging current flows at all times through the diode 21 and the resistor 22 into the capacitance 18. As the cycle progresses and the capacitance 18 accumulates a charge, the ungrounded terminal thereof increases in positive voltage relative to ground. The effect of the impression of this increasing positive voltage upon the control grid 17 of the tube 11 increases the magnitude of the space current flowing in this tube. As this current traverses the cathode-connected resistor 14, the voltage of the cathode is increased positively relative to ground. This increasing positive cathode voltage, when impressed by the coupling condenser 23 upon the upper terminal of the resistor 22, serves to maintain a relatively constant potential difference across this resistor, irrespective of the state of charge of the capacitance 18. By this means the magnitude of the charging current is maintained relatively constant.

As is well known, ordinarily the rate of change of the charging current flowing in a capacitive reactance circuit is in accordance with an exponential function so that as the charge accumulated by the capacitance increases, the rate of current flow decreases. However, by means of the described coupling of the resistor 22 to both the control grid and the cathode of the

tube 11, the charging current and, therefore, the voltage of the capacitance 18 varies at a relatively slow rate substantially according to a linear function. Since the voltage of the capacitance 18 controls the space current conduction in the tube 11, the voltages which are developed at the anode and cathode of this tube vary in a substantially linear manner. These voltages are, of course, of opposite phase and, therefore, are suitable for impression upon the terminals of the output circuit resistors 36 and 37 so as to supply this circuit with a push-pull voltage which is balanced relative to the grounded mid point of the load circuit. Inasmuch, as one-half of the output circuit voltage is derived from the anode of the tube 11 and the other half from the cathode of this tube, the effective magnitude of this voltage is substantially double the voltage which could be obtained from only one of these electrodes in a more conventional manner.

At the end of the relatively slow change of the generated output voltage, one of the positive impulses derived from the source 34 is impressed upon the control grid 32 of the tube 24, thereby rendering this tube conducting. There is provided by these means a relatively low impedance discharging circuit for the capacitance 18. Accordingly, the capacitance is discharged through the tube 24 and the resistor 25 at a relatively rapid rate to end the cycle. The apparatus functions in the manner described from this point for each succeeding cycle.

The diode 21, by reason of its unilateral conducting characteristic, is effective to enable higher voltage operation that if it were not used. At the peaks of the saw-tooth voltage cycles the combined, alternating and unidirectional voltages at the cathode of the diode may be considerably greater than the voltage of the battery 13 and, consequently, the diode-anode. The diode functions to permit this combined cathode voltage to develop, thereby extending the linear operating range of the saw-tooth wave generator.

Reference will now be made to Fig. 2 wherein another embodiment of the invention is disclosed. The circuit arrangement in this embodiment of the invention is particularly well suited for operation at relatively low frequencies of the order of 60 cycles per second, for example. Circuit components in this figure which correspond to circuit components in Fig. 1 have been given similar characters of reference. In general, the arrangement of the apparatus is much the same as that previously disclosed.

However, in view of the relatively low operating frequency the inherent capacity of the control grid 17 of the tube 11 to ground is inadequate to effect the generation of the desired saw-tooth voltage wave. In this instance, therefore, a condenser 39 is connected between the control grid 17 of the tube 11 and ground in the capacitive reactance circuit. Also a small condenser 41 is connected between the screen grid 16 of this tube and the positive terminal of the battery 13 and, in some cases, has been found to be helpful.

The load circuit comprises the series connection of two resistors 42 and 43. The junction point between these resistors is grounded as in the previous case and the other terminal of the resistor 43 is directly coupled to the cathode of the tube 11. No other cathode follower resistor is connected to the cathode of this tube. In

addition, the anode of the tube 11 is coupled to the other terminal of the resistor 42 through one or more glow discharge devices 44. These components may be neon tubes, voltage regulator tubes or the like. In such an arrangement the load circuit may be balanced relative to ground for alternating currents by making resistors 12 and 42 of 10,000 ohms and resistors 43 of 5,000 ohms. Resistors 12 and 42 are effectively coupled in parallel for alternating currents so that the impedance of the load circuit to ground from the anode of tube 11 is 5,000 ohms to match the impedance of the load circuit to ground from the cathode of the tube.

The operation of the apparatus illustrated in Fig. 2 is substantially the same as the described operation of the apparatus of Fig. 1. The condenser 39 is charged at a relatively slow rate through the circuit which includes the resistor 22. The voltage across the condenser 39, when impressed upon the control grid 17 of the tube 11, causes this tube to conduct more space current at a rate which increases substantially linearly. In this case, the space current is made to traverse the load resistor 43 by reason of its direct coupling to the cathode of the tube 11. Nevertheless, as in the previous instance, the voltage at the cathode of this tube increases with an increase in the space current conduction by the tube so as to maintain a substantially constant voltage drop across the charging resistor 22. The condenser 39 is discharged at a relatively rapid rate through the space discharge path of the tube 24 as in the case previously described.

The decreasing voltage at the anode of the tube 11 caused by the increasing current conducted by the tube is impressed upon the ungrounded terminal of the load resistor 42 through the glow discharge devices 44. All of such devices have the characteristic that once a predetermined threshold voltage is exceeded the impedance of the tubes, remains practically constant. Consequently, the anode voltage which is impressed upon the load circuit is not distorted by reason of having to traverse the glow discharge devices 44. Linearity of the saw-tooth voltage wave which is impressed upon the load circuit, therefore, is preserved.

Such a coupling arrangement is particularly useful when operating at relatively low frequencies. When conventional capacity coupling is employed it is necessary at such frequencies to use a relatively high value of capacitance so that the reactance may be kept small. Such condensers are bulky and, for this reason, are not generally desirable. Smaller condensers have larger reactances and thereby introduce a distortion in the voltage impressed upon the load circuit, whereby the desired high order of linearity is not obtained. Thus, it is apparent that the coupling facilities provided in accordance with this feature of the invention overcome the limitations of more conventional capacity couplings.

Furthermore, the combination of the particular types of input and output circuits for the tube 11 enable the generation of a push-pull saw-tooth wave of considerable voltage magnitude which is balanced relative to a datum potential and also has good linearity throughout the entire voltage range. As described, the circuit arrangement for maintaining the charging current flow in the capacitive reactance circuit at a substantially constant rate effects the generation of

a saw-tooth wave having the desired linearity characteristic. The provision of impedance devices connected respectively to both the anode and cathode of the tube enables the production of the saw-tooth wave in a push-pull manner and also at considerable voltage magnitude.

While there has been described what at present is considered the preferred embodiment of the invention, it will be obvious to those skilled in the art that various changes and modifications may be made therein without departing from the invention, and it is aimed, therefore, in the appended claims to cover all such changes and modifications as fall within the true spirit and scope of the invention.

What is claimed is:

1. A saw-tooth voltage generator comprising, a vacuum tube having an anode, a cathode and a control grid, a source of space current for said tube, a circuit including first and second impedance devices connected respectively to said anode and said cathode for coupling the space discharge path of said tube to said source of current, a circuit having capacitive reactance means and including a charging impedance device connected in series with said capacitive reactance means for supplying charging current thereto, one terminal of said charging impedance device being coupled to the control grid of said tube and the other terminal being coupled to the cathode of said tube, whereby a substantially constant potential difference is maintained between the terminals of said charging impedance device and as a consequence the rate at which current is supplied to said capacitive reactance means is maintained substantially constant, means for periodically discharging said capacitive reactance means a load circuit for said generator including the series connection of said second impedance device and a third impedance device, and means maintaining a constant voltage drop thereacross for limiting amplitude range of current flow connected between the anode of said vacuum tube and said third impedance device.

2. A saw-tooth voltage generator comprising, a first vacuum tube having an anode, a cathode and a control grid, a source of space current for said tube, a circuit including first and second impedance devices connected respectively to said anode and said cathode for coupling the space discharge path of said tube to respective terminals of said source of current, a capacitive reactance circuit including a condenser and a resistor connected in series therewith for supplying charging current thereto, one terminal of said resistor being coupled to the control grid of said tube and the other terminal being coupled to the cathode of said tube, whereby a substantially constant potential difference is maintained between the terminals of said resistor and as a consequence the rate at which current is supplied to said condenser is maintained substantially constant, means including a second vacuum tube for periodically discharging said condenser, a load circuit for said generator including the series connection of said second impedance device and a third impedance device, and means including a glow discharge tube for coupling the anode of said first vacuum tube to said third impedance device for maintenance across said glow discharge tube of a constant voltage drop for limiting amplitude range of current flow therethrough.

3. A saw-tooth voltage generator comprising, a first vacuum tube having an anode, a cathode and a control grid, a source of space current for said tube, a circuit including first and second impedance devices connected respectively to said anode and said cathode for coupling the space discharge path of said tube to respective terminals of said source of current, a capacitive reactance circuit including a condenser and a resistor connected in series therewith for supplying charging current thereto, one terminal of said resistor being coupled to the control grid of said tube and the other terminal being coupled to the cathode of said tube, whereby a substantially constant potential difference is maintained between the terminals of said resistor and as a consequence the rate at which current is supplied to said condenser is maintained substantially constant, means including a second vacuum tube connected to said capacitive reactance circuit and periodically being rendered conducting to discharge said condenser, a load circuit for said generator including the series connection of said second impedance device and a third impedance device, and means including a plurality of serially-connected glow discharge tubes for coupling the anode of said first vacuum tube to said third impedance device.

4. A saw-tooth voltage generator comprising, a first vacuum tube having an anode, a cathode and a control grid, a source of space current for said tube, a circuit including first and second resistors connected respectively to said anode and said cathode for coupling the space discharge path of said tube to respective terminals of said source of current, a capacitive reactance circuit including a condenser and a charging resistor connected in series therewith for supplying charging current thereto at a relatively slow rate, one terminal of said charging resistor being coupled to the control grid of said tube and the other terminal being coupled to the cathode of said tube, whereby a substantially constant potential difference is maintained between the terminals of said charging resistor and as a consequence the rate at which current is supplied to said condenser is maintained substantially constant, means including a second vacuum tube having its space discharge path connected in parallel with said condenser and periodically being rendered conducting to discharge said condenser at a relatively rapid rate, a load circuit for said generator including the series connection of said second resistor and a third resistor, and means including a plurality of serially connected glow discharge tubes for coupling the anode of said first vacuum tube to said third resistor.
